UNITED STATES PATENT OFFICE.

JEAN CARROTTE, OF NEW YORK, N. Y.

PAPER CONSTRUCTION.

968,644.

Specification of Letters Patent. Patented Aug. 30, 1910.

No Drawing.

Application filed April 23, 1909. Serial No. 491,772.

To all whom it may concern:

Be it known that I, JEAN CARROTTE, a citizen of the Republic of France, and resident of New York, in the county of New York and State of New York, have invented certain new and useful Improvements in Paper Construction, of which the following is a specification.

This invention relates to improvements in paper construction and has for its principal object to construct a paper having high tearing resistance quality.

This invention is applicable to any of the standard makes of paper.

The method of manufacturing consists primarily in passing around the drum upon which the pulp is being received a woven fabric wherein the warp threads are extended longitudinally and parallel each to the other while the woof threads are woven through the warp threads in a diagonal or inclined position. The angle at which the woof threads are placed in the woven fabric is not defined. It is found that the highest resistant qualities are produced by the more acute angles of the position of the woof threads relative to the warp threads.

The fabric may be constructed from any suitable material. When employed by me in the manufacture of high quality of paper, such as bond paper, a very fine threaded silk is used. Again the mesh of the threads is adapted to the use for which the paper is designed. The closer the mesh the stronger the paper. The woven fabric is placed in the paper or pulp body about midway in the process of the manufacture of the paper. The pulp in the course of manufacture is forced through all of the interstices or mesh of the body of the fabric, so that the woven fabric becomes in a sense a constituent of the body of the paper.

Various degrees of strength are provided in this paper. Wherein an increased strength over and above that provided in the paper constructed as above is desired, I add a second layer of fabric woven in the same manner as set forth. But in laying the second layer of fabric, care is taken to so dispose the layers that the warp threads

extend parallel each to the other in the two layers while the woof threads are caused to cross the woof threads in the layer first applied. The two layers may be interposed 55 in the pulp simultaneously but I prefer to place them successively, allowing a thin layer of pulp paper to be laid over the first layer of fabric. When two layers of the fabric are thus constructed in the body of the 60 paper, there is produced an article which it is practically impossible to tear.

While I have herein above described the use of two layers of cloth woven in the manner described, I wish to be understood as 65 also claiming the use of a single layer of the said cloth in combination with a single layer of the cloth of the usual construction, wherein the warp and the woof threads are crossed at an angle of 90 degrees, or per 70 perpendicular each to the other.

I am well aware that papers have been manufactured wherein threads have been placed between layers of paper and incorporated in the body thereof, also that woven 75 threads have been so disposed in paper. I am also aware that a fabric having warp and woof threads disposed at an angle other than the usual angle of ninety degrees have been made and such constructions and arrangements I do not broadly claim.

Having thus described this invention, what is claimed is:

A reinforced non-elastic paper comprising a plurality of layers of textile fabric woven 85 so that the warp and woof threads are disposed in an angular relation other than that of ninety degrees, said layers being superimposed so that the woof threads of each layer are extended across the woof threads 90 of the other layer and the warp threads in both layers are parallel; the said fabrics being woven with open mesh, and said paper being homogeneously formed and holding the fiber of said fabrics in fixed relation. 95

Signed at New York in the county of New York and State of New York this 22nd day of April A. D. 1909.

JEAN CARROTTE.
